IMPROVEMENT IN SPRINGS FOR HAT BRIMS.

SAMUEL PECK, OF NEW HAVEN, CONNECTICUT.

Letters Patent No. 60,236, dated December 4, 1866.

SPECIFICATION.

TO ALL WHOM IT MAY CONCERN:

Be it known that I, SAMUEL PECK, of New Haven, in the county of New Haven, and State of Connecticut, have invented a new Improvement in Springs for Hat Brims; and I do hereby declare the following, when taken in connection with the accompanying drawings, and the letters of reference marked thereon, to be a full, clear, and exact description, and which said drawings constitute part of this specification, and represent the manner of forming the spring.

My invention relates to an improvement in forming the spring for distending hat brims, whereby a graceful curvature is given to the brim, and consists in the peculiar manner of forming the wire, so that at the required point the wire is curved in the proper direction by drawing it thinner or stretched upon the convex edge; and to enable others skilled in the art to construct and use my improvement, I will proceed to describe the same, as illustrated in the accompanying drawings.

The wire which I employ is the ordinary flat steel or hoop-skirt wire, as denoted in red in the drawings; this I pass between rollers or other device for reducing or stretching wire, say starting from the point *a*, and the rollers formed so as to make the upper or convex side longer (or stretched) than the lower or concave, as at 1, gradually running out until the point *b* is flat, as at 2; from this point the opposite side becomes the convex side, and is rolled from the point *b* to the point *c*, gradually decreasing the thickness of or stretching the convex edge, as at 3, and from the point *c*, to the point *d*, when the wire is again flat or of an even thickness, and then again, reversing, the extreme thinness of the convex edge is reached at the point *e*, returning to an even thickness at the point *f*, again reversing, forming the convex surface *g*, and returning again to an equal thickness at the point *h*, and reversing again to the point *i*, which corresponds to the place of beginning, and completes the wire for the formation of the hoop or spring, which is done by uniting the two ends, *a* and *i*, in the usual manner; these two points united, correspond to the central point, *e*, and form opposite sides of the brim, while the points *c* and *g* are drooping to the front and rear. This formation of the wire may be continued through an entire length of wire and then cut at the proper points. This curve has heretofore been given by holding the wire at the two ends and the centre, then twisting the wire midway between the centre and the two ends, but in thus twisting the wire there is an uncertainty about the perfection of shape, inasmuch as the wire is unavoidably of an uneven temper; so that unless great care is exercised, the twist will be proportionately uneven, while by my invention the curve is certain without regard to the temper of the wire, and it may be rolled, as before stated, into this form while in the process of drawing, and therefore curved, at no additional expense, and after having been so curved may be covered, if desired, in the usual manner, and when the hoop is complete, it is applied to the hat brim as similar springs are usually applied.

I do not claim the employment of a flat steel spring for distending hat brims, neither do I broadly claim giving a droop to the front and rear of a hat brim, by means of a steel-wire spring. But having thus fully described my invention, what I do claim as new and useful, and desire to secure by Letters Patent, is—

Forming springs for hat brims, so as to droop at the front and rear, by curving the wire, substantially as herein set forth.

SAML. PECK.
